Primary Examiner — T Chase Nelson(74) *Attorney, Agent, or Firm* — Banner & Witcoff, Ltd.(57) **CLAIM**

The ornamental design for a shoe, as shown and described.

DESCRIPTION

FIG. 1 is a bottom rear perspective view of a shoe showing my new design;

FIG. 2 is a bottom view thereof;

FIG. 3 is a bottom front perspective view thereof;

FIG. 4 is a bottom rear perspective view of a shoe showing my new design in an alternate embodiment;

FIG. 5 is a bottom view thereof; and,

FIG. 6 is a bottom front perspective view thereof.

The broken line immediately adjacent to the front of the shaded area defines the bounds of the claimed design and forms no part thereof. The broken lines depicting the remainder of the shoe form no part of the claimed design.
